DESIGN FOR A COMBINED AIR FILTER AND COOLER

John Connor Austin, Oklahoma City, Okla.

Application August 31, 1936, Serial No. 64,652

Term of patent 3½ years

To all whom it may concern:

Be it known that I, John C. Austin, a citizen of the United States, residing at Oklahoma City, in the county of Oklahoma and State of Oklahoma, have invented a new, original, and ornamental Design for a Combined Air Filter and Cooler, of which the following is a specification, reference being had to the accompanying drawing, forming a part thereof.

Figure 1 is a front perspective view of a combined air filter and cooler showing my new design; and,

Figure 2 is a rear perspective view thereof.

The characteristic features of my design reside in the cabinet as shown having a front portion comprising four substantially triangular inwardly inclined planes terminating in a circular opening; and an all-over mesh rear portion.

I claim:

The ornamental design for a combined air filter and cooler, as shown and described.

JOHN CONNOR AUSTIN.
